UNITED STATES PATENT OFFICE.

GEORGE L. LAKE, OF NEW MARKET, IOWA, ASSIGNOR OF ONE-HALF TO ELMER C. EIGHMY, OF NEW MARKET, IOWA.

AUTOMOBILE-RADIATOR.

1,390,794.

Specification of Letters Patent. Patented Sept. 13, 1921.

Application filed July 15, 1920. Serial No. 396,394.

To all whom it may concern:

Be it known that I, GEORGE L. LAKE, a citizen of the United States, resident of New Market, in the county of Taylor and State of Iowa, have made a certain new and useful Invention in Automobile-Radiators; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a front view of the invention. Fig. 2 is a section on the line 2—2, Fig. 1, enlarged and partly broken away.

Fig. 3 is a detail cross sectional view of several of the radiator tubes. The invention has relation to radiators for the explosive engines of motor vehicles, having for an object to provide improved radiator tubes adapted to expand under pressure and thereby resist bursting; to increase the water capacity of the radiator; to arrange the radiator tubes in such manner as to increase the circulation of the air relative to each tube and thereby facilitate the cooling of the water contents of the tubes; and to provide the radiator casing with removable front and back plates, and the radiator tubes with longitudinal seams or joints facing forwardly and rearwardly and readily accessible for repairing in case of bursting.

The invention consists in the novel construction and combinations of parts, as hereinafter set forth.

In the accompanying drawings, illustrating the invention, the numeral 2 designates the hollow top of the radiator casing; 3 the hollow bottom thereof, and 4, 4 the upright series of tubes connecting the top and bottom, the frame of the casing comprising also sides 5, 5, connecting top and bottom thereof, and intermediate horizontal partitions 6, 6, being used to assist in maintaining the tubes in proper relation.

The front of the casing of the radiator is provided with a recess 7, wherein fits a removable front plate 8, having the usual openwork formation, and the rear or back of the casing is also provided with a recess or seat 9, wherein fits a removable back plate 10, of openwork formation, horizontal bolts

11 engaging apertures 12 of the sides of the casing and having each one end threaded at 13 into apertures of the removable front, and the other end engaging apertures 14 of the removable back and threaded for engagement of nuts 15.

The radiator tubes are arranged in inclined series 16, each series having a central bend 16' therein, whereby it is divided into two wings or branches 17, 17, angularly disposed, and each series of tubes is composed of members arranged close together. The series of tubes, bent or bowed as stated, are spaced apart by bowed intervals 18 considerably wider than the spaces 19 separating the members of each series. As a result, the air currents passing through the radiator not only have more direct impingement upon the tubes, but the passage of the air currents in straight paths through the radiator casing is guarded against to a maximum extent.

Each of the radiator tubes is made of sheet metal, bent into form and provided with a longitudinal seam or joint 20, which in the case of the members of the wing or branch of the bent series nearest the removable front of the radiator casing is arranged to face said front, and in the case of the wing or branch of the series nearest the removable back of said casing is arranged to face said back, whereby, should a break develop in any of the tubes, it will be readily accessible for repairs, upon removing the front or back of the casing, as may be needed.

Each of the radiator tubes is made in squared or quadrangular form, with a corrugation or groove 21 in each side, the metal of said corrugation or groove being expandible under pressure, and thereby resisting bursting.

I claim:

1. An automobile radiator, having a front plate, a rear plate, upright radiator tubes arranged in inclined series, each series having a central bend and angularly disposed branches, and a hollow top and a hollow bottom, having communication with said tubes, side frame pieces connecting said top and said bottom, said tubes being of sheet metal and having longitudinal joints all accessible from the front and rear of the radiator upon removal of the front and of the rear plate.
2. An automobile radiator having a front

plate, a rear plate, upright tubes arranged in inclined series, each series having a central bend and angularly disposed branches, and a hollow top and a hollow bottom having communication with said tubes, side frame pieces connecting said top and said bottom, said tubes being of quadrangular form provided with longitudinally grooved sides expandible under pressure, the tubes being of sheet metal and having longitudi-

nal joints all accessible from the front and rear of the radiator upon removal of the front and of the rear plate.

In testimony whereof I affix my signature in presence of two witnesses.

GEORGE L. LAKE.
